UNITED STATES PATENT OFFICE

2,076,696

SHOE PRESS

Pincus Brauner, Haverhill, Mass.

Application November 16, 1934, Serial No. 753,263

9 Claims. (Cl. 12—33)

This invention relates to shoe presses or jacks for holding an outer sole firmly against a shoe during the cementing operation.

In manufacturing shoes and in repairing shoes it is quite common to cement the outer sole in place, and when cement is employed to permanently secure the sole to a shoe it is important that the sole be held tightly against the bottom of the shoe throughout the period required for the cement to set. To accomplish this it has been proposed heretofore to employ a press or jack having an inflatable bag or pad to press the sole firmly against the shoe.

When the bag of a shoe press is inflated with a shoe resting thereon it is necessary to hold the shoe from moving upwardly under the pressure exerted upon the sole by the bag, and various forms of adjustable levers and screws have been proposed heretofore for holding the shoe in place.

The present invention contemplates an extremely simple form of shoe press or jack which is so designed that the adjustable shoe holding levers and screws employed heretofore are eliminated in the present construction.

One important feature of the invention resides in a shoe press or jack consisting of a base for supporting an inflatable bag and an overhanging arm of the cantilever type which extends over the base far enough to overlie and hold both the toe and heel parts of the shoe.

Another important feature resides in the construction and arrangement whereby shoes of various sizes may be placed in the press without requiring any provision for adjustment between the base and shoe holding means extending over the base.

A further feature resides in the novel construction of the bag and cooperating base that holds and supports the bag, and still a further feature resides in the construction and arrangement of pipe means for inflating and deflating the bag.

Other features of the invention and novel combination of parts in addition to the above will be hereinafter described in connection with the accompanying drawings which illustrate good practical forms thereof.

In the drawings:

Fig. 1 is a perspective view of a press or jack of the present invention showing a shoe in place and the bag inflated.

Fig. 2 is a side elevation of Fig. 1.

Fig. 3 is a perspective view of the inflatable bag employed in the jack of Fig. 1.

Fig. 4 is a sectional view taken on the line 4—4 of Fig. 3.

Fig. 5 is a side elevation of a modified form of jack constructed to be mounted on a supporting table and to receive a shoe with the heel in place; and

Fig. 6 is a side elevation of a further modification showing the supporting means for the jack at the closed end of the casting.

In each of the constructions shown practically the entire jack is formed of an integral casting consisting of a bag supporting base 10, an upright portion at one end of the base and an overhanging arm or cantilever that is supported in spaced relation to the base by the upright. 10 In Figs. 1 and 2 this upright is designated by 11 and the overhanging arm or cantilever is designated by 12, and in order to secure a strong jack of light weight the parts 11 and 12 may have an I-beam construction in cross section as shown, and the parts 11 and 12 are shaped to form a graceful curve while the lower portion of the upright 11 has a rib-like part 13 that extends under the base 10 to support and strengthen this base. As a result of this construction the jack somewhat resembles the letter C in side elevation and provides an entrance opening through which a shoe can be readily inserted and removed.

The bag supporting base 10 preferably has a relatively flat surface below the sole of the shoe upon which the bag rests and has the upstanding side walls or flanges 14 and 15 adapted to support the sides of the bag when the bag is inflated. At the inner end of the base is preferably provided the upstanding wall 16, and extending inwardly a short distance from this wall is the shelf 17 that overlies the end of the bag and is elevated sufficiently to permit this end to curl upwardly slightly about the toe of the shoe when the bag is inflated, but prevents this end from curling too much. The portion of the base 10 which supports the heel portion of a shoe is preferably curved upwardly somewhat as shown so as to hold the bag up firmly against the shank of the shoe, and the outer end of this base may have the curved upwardly extending flange 18 that conforms to the rounded end of the inflated bag.

The outer end portion of the cantilever arm 12 preferably curves downwardly somewhat as shown and is shaped to provide the abutment 19 adapted to be engaged by the heel part of a last L when the shoe S in which this last is inserted is forced upwardly by an inflated bag or pad B. The toe portion of the shoe is held against the upward

pressure of the bag, in the construction shown, by the post 20 which is slidably mounted upon and extends downwardly from an intermediate portion of the cantilever arm 12. The post 20 is 5 slidably secured to the overhanging arm 12 by providing at the upper end of the post a head 21 that is slidably secured to a block-like portion 22 of the arm 12 by the tongue and groove parts shown. As a result of this construction the post 10 20 may be readily shifted lengthwise of the jack to accommodate different size shoes. The lower end of the post 20 is preferably provided with a soft pad 23 adapted to engage the shoe.

The means for supporting the shoe press or jack 15 may vary in accordance with the use to which the jack is to be put, and in the construction shown in Figs. 1 and 2 the jack is provided with the supporting bracket 24 that extends upwardly some distance from the upper part 12 of the jack. This 20 construction is particularly well adapted for supporting the jack from the periphery of a wheel as in the sole cementing machine forming the subject matter of my application Serial No. 756,965 filed December 11, 1934.

25 In the modification of Fig. 5 the upright is designated by 11^a and the overhanging arm by 12^a, and a jack supporting bracket 28 is provided beneath the base 10 and is secured by the bolts 29 to a supporting plate or table 30.

30 It is important that means be provided for inflating and deflating the bag B and this is accomplished in the construction shown in Fig. 5 by forming an air conduit 31 in the lower portion of the jack frame, and this conduit may be formed 35 by providing a hole extending upwardly through the bracket 28 and rib 13 to the clearance space 32 formed in this rib, or by providing a pipe which is cast in the metal of the casting. The lower end of the conduit 31 aligns with a hole 33 in the table 40 30 to which air under pressure may be supplied by the pipe 34, and a gasket X is provided between the parts 28 and 30.

In the modified form of Fig. 6 the upright is designated by 11^b and the overhanging arm by 45 12^b, and the jack is supported by a bracket 25 provided at the inner end of the jack and this bracket is secured by bolts 26 to supporting means 27. In this construction a ferrule 35 is cast in the rib 13 below the clearance space 32. This 50 ferrule is closed at its lower end and open at its upper end and air under pressure is supplied to the ferrule by a pipe 36 which is preferably cast in the metal of the casting and extends from the outer face of the flange 25 to the ferrule. The end 55 of this pipe within the flange 25 is preferably secured to a metal disk 37 which is secured in the casting and the metal forming the ferrule 35, pipe 36 and disk 37 should have a much higher melting point than the metal forming the jack casting so that these parts will not be injured where they 60 are surrounded by the molten metal of the casting.

In the construction shown in Figs. 1 and 2 the air supply pipe 38 positioned in the jack casting leads from a disk 39 at the upper face of the flange 24 to a ferrule 40 below the clearance space 65 32. This ferrule however is shown as provided with the hand valve 41 which may be opened to allow the compressed air to escape from the bag B.

70 The construction of the inflatable bag is important since it is found advisable to inflate the bag under considerable pressure, and the bag will not stand this pressure unless it is well designed. In the construction shown the bag comprises a 75 bladder 42 of rubber and a casing 43 preferably

formed of leather. The major portion of the casing 43 is formed of a single strip of leather rectangular in shape and folded over upon itself so that its ends overlap at the under side of the bag as at 44 and the overlapped ends are 5 cemented together. This produces a container having the form of a relatively flat tube and the ends of the tube thus formed are closed by securing in these ends the long narrow leather strips 45 which are curved longitudinally as shown to 10 give the bag the configuration shown in Fig. 3 to conform to the bottom of the shoe. These strips 15 45 are secured to the parts 43 by the rows of stitches 46 as best shown in Fig. 4. The bag may have its greatest fullness below the shank of the 15 shoe as shown.

The bag thus formed has the smooth rounded 20 ends 47 that are free from seams or joints, and the bladder is inserted in the casing through the slit 48 closed by the lacing 49. The bladder 42 20 may have the usual metal valve tube 50 from which the internal valve is omitted and which tube is externally threaded and has screwed thereupon the locking nut 51. This nut in accordance with the present invention performs the 25 double function of clamping the bag in place upon the base 10 and of forming an air tight connection between the outer end of the tube 50 and the pipe 31 of Fig. 5 or the ferrules of the other views. In each case a pocket or seat is formed at 30 the lower side of the clearance opening 32 to receive a non-metallic washer 52 against which the lower end of the tube 50 is tightly seated by tightening the nut 51 against the upper wall of the opening 32. In this manner a simple means 35 of providing an air tight connection between tube 50 and supply pipe is secured.

While the jack of the present invention was 40 designed more particularly to employ air as the bag inflating fluid, satisfactory result may be secured by inflating the bag with a liquid such as water, particularly if the bag is connected with the water supply system that is under a constant head pressure which maintains the pressure in the bag. 45

In the modified form of Fig. 5 the supporting base 10 and bag B are shorter than in the other views so as to clear the heel of a shoe in case it is desired to secure a sole to a shoe which has the heel attached. 50

It will be seen from the foregoing that the present press or jack has very few parts and will receive shoes of various sizes and shapes without any adjustment other than possibly the sliding movement of the post 20. It will also be apparent that the box-like construction of the base 10 serves to support the sides of the bag while the bag is sufficiently free to conform snugly to the 55 contour of the shoe.

While the shoe press of the present invention 60 has been described as designed to hold the sole firmly against a shoe while the binding cement sets, the press may be employed for the purpose of pressing the lower edges of the shoe upper firmly against the last to shape the shoe. It may 65 also be employed to press the sole firmly against the shoe when a rubber or other quick acting cement that grips immediately is used.

I claim:

1. A shoe press for pressing a sole against 70 a shoe to cement the sole in place, comprising an inflatable bag, a casting formed with a base for supporting the bag and an overhanging cantilever arm that extends over substantially the entire length of the base and provided with a 75

rigid last-receiving abutment at its outer end to hold a shoe against the upward pressure exerted upon it when the bag upon the base is inflated.

2. A shoe press for pressing a sole against a shoe to cement the sole in place, comprising an inflatable bag, a casting formed with a longitudinally extending base for supporting the bag and an integral cantilever arm that extends over substantially the entire length of the base and provided with a rigid last-receiving abutment at its outer end to hold a shoe against the upward pressure exerted upon it when the bag upon the base is inflated.

3. A shoe press for pressing a sole against a shoe to cement the sole in place, comprising an inflatable bag, a casting formed with a longitudinally extending base for supporting the bag and a cantilever arm that extends over substantially the entire length of the base and provided with a rigid last-receiving abutment at its outer end to hold a shoe against the upward pressure exerted upon it when the bag upon the base is inflated, and said casting being opened at one end for the passage of the shoe into and out of the press.

4. A shoe press for pressing a sole against a shoe to cement the sole in place, comprising a bag having an externally threaded tube extending downwardly therefrom and a clamping nut on the tube, a casting having a base for supporting the bag and formed with a clearance space below the base for the clamping nut, a pipe for inflating the bag mounted in the casting and having its discharge end aligned with said tube whereby a tight joint is formed between the tube and pipe by tightening the clamping nut against the casting in a direction to force the tube downwardly and seat it firmly at the end of said pipe, and means for holding a shoe upon the inflated bag.

5. A shoe press for pressing a sole against a shoe to cement the sole in place, comprising a bag having a tube extending therefrom, a casting having a base for supporting the bag and an upwardly extending portion for carrying means for holding a shoe upon the inflated bag, means for supporting the casting from said upwardly extending portion, and a pipe cast within the casting and

extending from said supporting means to said tube to inflate the bag.

6. A shoe press for pressing a sole against a shoe to cement the sole in place, comprising a bag having a tube extending therefrom, a casting having a base for supporting the bag, a pipe cast within the casting and connected to said tube to inflate the bag, a valve connected to said pipe, and means for holding a shoe upon the inflated bag.

7. A shoe press for pressing a sole against a shoe to cement the sole in place, comprising an inflatable bag, a base for supporting the bag, an upright at one end of the base and formed with a supporting flange that projects under the base and is integral with the latter, and an arm supported entirely by said upright in overhanging relation to the base and constructed and arranged to extend over the base far enough to overlie both the toe and heel parts of a shoe and hold them against the upward pressure exerted upon the shoe by the inflated bag.

8. A shoe press for pressing a sole against a shoe to cement the sole in place, comprising an inflatable bag, a base for supporting the bag, said bag and base being adapted to support a shoe with the heel attached, an upright at one end of the base, and a cantilever arm supported by said upright in overhanging relation to the base and constructed and arranged to extend over the base and beyond the other end thereof to overlie both the toe and heel parts of a shoe to form a shoe-receiving opening between the end of the base and arm and hold the shoe and last against the upward pressure exerted upon the shoe by the inflated bag.

9. An inflatable bag for a shoe cementing press, comprising a bladder, a casing therefor formed of an elongated strip of leather having its ends secured together in overlapping relation at a point along its lower wall to provide a flattened tube having rounded seamless ends, and the side openings of the flattened tube thus formed being closed with long narrow strips secured therein to form an elongated bladder-containing casing.

PINCUS BRAUNER.
